UNITED STATES PATENT OFFICE

ROBERT G. WILLIAMS, OF TOLEDO, OHIO

DESIGN FOR A FLASH LIGHT LANTERN

Application filed June 16, 1932. Serial No. 44,096. Term of patent 3½ years.

To all whom it may concern:

Be it known that I, ROBERT G. WILLIAMS, a citizen of the United States, residing at Toledo, in the county of Lucas and State of Ohio, have invented a new, original, and ornamental Design for Flashlight Lanterns, of which the following is a specification, reference being had to the accompanying drawing, forming part thereof.

Fig. 1 is a front elevational view of a flashlight lantern showing my new design;

Fig. 2 is a side elevation of the flashlight lantern showing my new design, and

Fig. 3 is a perspective view of the flashlight lantern.

I claim:

The ornamental design for a flashlight lantern, as shown.

ROBT. G. WILLIAMS.
